TOOL FOR SEVERING METAL BANDS ON
CRATES AND THE LIKE

Joseph A. Fanelli, Des Moines, Iowa

Application August 2, 1951, Serial No. 240,021

3 Claims. (Cl. 81—3)

(Granted under the act of March 3, 1883, as
amended April 30, 1928; 370 O. G. 757)

1

The invention described herein, if patented, may be manufactured and used by or for the Government for governmental purposes, without the payment to me of any royalty thereon.

My invention relates to tools, and more particularly to a tool for use in severing metal bands of the type used to secure boxes, crates and the like during shipment.

A primary object of the invention is to provide a simplified multi-purpose tool which is particularly useful for opening heavy wooden crates, and embodying novel means to sever or snap the steel bands which surround the crates during shipment.

A further object is to provide a tool of the above-mentioned character having means readily engageable with a taut metal band, and constructed to lift and positively hold the band so that the same may be tensioned and flexed until failure occurs.

A still further object of the invention is to provide a hand tool of the above-mentioned class which is easy to manipulate, sturdy and durable in construction and inexpensive to manufacture.

Other objects and advantages of the invention will be apparent during the course of the following description.

In the accompanying drawings, forming a part of this application, and in which like numerals are employed to designate like parts throughout the same:

Figure 1 is a side elevation of a tool embodying my invention, part broken away.

Figure 2 is a fragmentary transverse vertical section taken on line 2—2 of Figure 1.

Figure 3 is a side elevation of the tool illustrating the use of the same for severing a metal band upon a crate or the like.

Figure 4 is a fragmentary sectional view taken substantially on line 4—4 of Figure 3.

Figure 5 is a side elevation of a tool embodying a slight modification of the invention.

Figure 6 is an end elevation of the tool illustrated in Figure 5, and,

Figure 7 is a side elevation of a tool embodying a further modification of the invention.

In the drawings, where for the purpose of illustration are shown preferred embodiments of my invention, attention is directed first to Figures 1 to 4 inclusive, wherein the numeral 10 designates generally the body portion of my multi-purpose tool, which preferably is in the form of a hatchet. The body portion 10 has the usual relatively narrow forward cutting blade 11, and is provided at its opposite end with a flat relatively wide thick head 12 for driving nails and the like. At the

2

inner side of the head 12 nearest the handle 13 of the tool, the head is provided with a pair of curved laterally extending nail-pulling claws 14.

The body portion 10 is provided in its outer longitudinal edge 18 with a generally longitudinal narrow slot 15, which extends from a point near and longitudinally inward of the hammering surface of the head 12 to a point near the longitudinal axis of the handle 13. The innermost portion 16 of the slot 15 is straight, and arranged perpendicular to the hammering surface of the head 12 and to the longitudinal axis of the handle 13. The straight portion 16 of the slot 15 is substantially parallel to the outer longitudinal edge 18 of the body portion, while the entrance portion of the slot is inclined relative to the longitudinal edge 18. The length of the straight portion 16 of the slot is preferably substantially equal to the width of the metal band to be severed by the tool, as will be more fully described hereinafter. The entrance portion of the slot 15 is curved and leads laterally inwardly of the longitudinal edge 18 gradually, while extending longitudinally thereof for a substantially greater distance. The slot 15 extends through the opposite side faces 17 of the body portion 10, and the opposed surfaces of the slot are normal to the side faces 17, Figure 3. Squared or sharp cutting corners 17' are formed along the entire length of the slot 15, where the opposed surfaces of the slot meet the side faces 17. The opposed surfaces of the slot 15 are smooth and parallel over their entire areas, and the width of the slot is preferably only slightly greater than the thickness of the band to be severed.

The slot 15 forms with the outer longitudinal edge 18 an elongated tapered cam element or wedge 19 having a substantially sharp transverse leading edge 20, for engagement under a taut steel band 21 which surrounds a crate 22 or the like. The outer end 23 of the head 12 terminates laterally inwardly of the leading edge 20, as shown, so that the wedge 19 may more readily pass beneath the taut metal band 21, when the band is lying flat against a side of the crate 22. The end 23 is flat, and arranged at right angles to the hammering or working surface of the head 12. The entire slot 15 is arranged relatively near the outer longitudinal edge 18 of the body portion 10, and the tapered wedge 19 is relatively narrow so that the wedge may be introduced under the taut band 21 without too much effort, and without necessitating lifting the taut band from the adjacent side of the crate to any great extent.

In use, the handle 13 may be directed upwardly

as shown in Figure 4, with the longitudinal edge 18 and wedge 19 arranged next to one side of the crate 22. The tool is then shifted transversely of the band 21 to be severed with the leading edge 20 of the wedge directed forwardly and sliding along the adjacent side of the crate. The leading edge 20 will now engage under the taut band 21 and as the tool continues to be shifted transversely, the same is forced upwardly over the curved inclined surface of the wedge 19 and will ultimately engage the inner most end of the slot 15, as shown in Figure 4. The band 21 is now disposed in the straight portion 16 of the slot and extends beyond the opposite side faces 17. While in such position, the band 21 has no tendency to spring or slip out of the slot 15, since the tension in the band is downward and normal to the side walls of the straight portion 16 of the slot. As previously stated, the width of the slot 15 is preferably only slightly greater than the thickness of the band, and this further reduces the tendency for the band to slip laterally or longitudinally within the slot.

While the band 21 is thus engaged within the straight portion 16 of the slot, the handle 13 is grasped as in Figure 3 and the tool is rocked about the longitudinal edge 18 of the body portion 10, as shown, until failure of the band 21 occurs. The band will bend at the sharp corners 17' when the tool is rocked, and failure will be induced by a combined cutting, bending and tensioning action. It is frequently necessary to rock the tool about its lower end only one time and in one direction to cause the failure of the band 21.

In Figures 5 and 6, I have shown a slight modification of the invention, wherein the band-receiving slot 25 is formed in the relatively narrow cutting blade portion 11. The slot 25 is identical in curvature and length with the slot 15, and the leading sharpened edge 25' of the wedge element 26 projects laterally beyond the adjacent end of the cutting blade 11, in a manner similar to the disposition of the leading edge 20. The chief difference in the construction shown in Figures 5 and 6 is that the slot 25 and tapered wedge 26 are relatively narrower than the slot 15 and wedge 19, the former being formed in the relatively narrow cutting blade portion 11 of the tool, while the latter are formed in the thicker head portion 12. Also, as best shown in Figure 6, the wedge 26 tapers longitudinally toward the cutting edge of the blade 11. As in the first form of the invention, sharp corners are formed where the opposed surfaces of the slot 25 meet the side faces of the cutting blade 11, and this aids in the severing of the metal band. The use or operation of the form of the tool illustrated in Figures 5 and 6 are substantially identical to that described in connection with the first form of the invention.

In Figure 7, there is shown a further modification of the invention, wherein the band-receiving slot 28 is formed in the relatively thick head portion 12, as in the first form of the invention. In Figure 7, however, the slot 28 is arranged at an angle with respect to the side faces 17 of the body portion 10, rather than normal thereto. Sharp corners 29 are formed where the opposed surfaces of the slot 28 meet the side faces 17. The chief advantage of the construction illustrated in Figure 7 resides in the fact that when the tool is rocked during the use of the same the angle A between the metal band 21 and adjacent side face 17 is more acute than the corresponding angle in connection with the first form of the invention, where the slot 15 is normal to the side

faces 17. The arrangement causes a greater degree of bending of the band 21, greater tensioning of the band and more cutting action at the corners 29. Hence failure of the band 21 is produced more readily and with less rocking of the tool.

It is to be understood that the forms of the invention herewith shown and described are to be taken as preferred examples of the same, and that various changes in shape, size and arrangement of parts may be resorted to, without departing from the spirit of the invention or the scope of the subjoined claims.

Having thus described my invention, I claim:

1. A tool for severing a taut metal band comprising a body portion provided in one side with a slot which extends laterally inwardly of said side and generally longitudinally thereof, the innermost portion of the slot being straight and generally parallel to said side for accommodating the entire width of the band when the band enters the slot, the slot forming with said side a tapered wedge for engagement beneath the band so that the band is forced into the innermost straight portion of the slot when the wedge moves transversely of the band, the free end of the tapered wedge projecting beyond said side of the body portion to facilitate the passage of the wedge under the band, there being substantially sharp corners formed where the opposed faces of the slot meet the opposite sides of the body portion, and a handle secured to the body portion for rocking the same about said side having the slot.

2. A tool for severing a metal band surrounding a crate or the like comprising a body portion provided in one side with a narrow slot having a width only slightly greater than the thickness of the metal band, the slot having an entrance portion which is inclined with respect to said one side of the body portion and extending laterally inwardly of said one side and generally longitudinally thereof, the slot including an innermost straight portion of a length sufficient to accommodate the entire width of the metal band when the band reaches the inner end of the slot and extends transversely through the same, the slot forming with said one side of the body portion an elongated tapered wedge for engagement under the band so that the band is forced upwardly and into the straight portion of the slot, the leading end of the tapered wedge projecting laterally beyond said one side of the body portion, there being sharp corners formed where the opposed surfaces of the slot meet opposite faces of the body portion.

3. A tool for use in severing metal bands surrounding crates or the like comprising a body portion provided in one side with a slot, said slot having an inclined entrance portion extending laterally inwardly and generally longitudinally of said one side and an innermost straight portion for receiving and holding the metal band, the innermost straight portion being generally parallel to said one side of the body portion, the entire slot being transversely inclined with respect to the opposite side faces of the body portion so that tilting of the body portion laterally while the metal band is disposed within the slot will form an acute angle between said band and the adjacent side face of the body portion.

JOSEPH A. FANELLI.
